UNITED STATES PATENT OFFICE

HARRY GUY BARTHOLOMEW, OF LONDON, ENGLAND

PHOTOTELEGRAPHY

Application filed October 30, 1926, Serial No. 145,184, and in Great Britain December 17, 1925.

My invention relates to a new and improved method of photo-telegraphy and a new and improved apparatus for this purpose.

One of the objects of my invention is to provide a new and improved method whereby pictures can be recorded or sent by a series of electric pulses, in which greater detail will be secured.

Another object of my invention is to provide a method of telautography or photo-telegraphy whereby a non-pictorial record will be formed or electrical pulses will be produced corresponding not only to spaced parallel rows of the small areas of the picture or the like which is to be recorded or transmitted, but also corresponding to the areas or lines of the said picture which are between the said spaced parallel rows.

Another object of my invention is to provide for an improved reproduction of the picture or the like which has been transmitted, or recorded in non-pictorial form.

Other objects of my invention are to produce improvements in that system or method of photo-telegraphy or telautography disclosed, for example, in British Patent No. 195,577.

Other objects of my invention will be set forth in the following description and drawings which illustrate a preferred embodiment thereof, it being understood that the above general statement of the objects of my invention is intended merely to generally explain the same and not to limit it in any manner.

Figs. 1-5 diagrammatically illustrate the progressive "lateral" variation of the reader points utilized in connection with my improved method, from what may be termed the standard position.

Figs. 6-10 illustrate what may be termed the "longitudinal" variation of said reader points from the standard position.

Fig. 11 diagrammatically illustrates the relative locations of the reader points.

Fig. 12 diagrammatically illustrates the improvement in the reproducing apparatus.

Fig. 13 diagrammatically illustrates the relative locations of the shutter-controlled openings used in connection with the repro-

ducing apparatus. This is a section on the line 13-13 of Fig. 12.

Fig. 14 diagrammatically illustrates the light images formed upon the light sensitive film according to my new and improved method.

Fig. 15 illustrates the record tape.

The before mentioned British Patent No. 195,577, as well as other patents, illustrate the well known "Bartlane" process for making non-pictorial records of pictures and for transmitting pictures by means of photo-telegraphy. According to this method, a series of prints of varying darkness are produced from a picture by exposing said prints for varying lengths of time to the action of light. Hence, one of these prints, which may be called the first print, and which is exposed for the shortest period of time, only records the brightest tones of the picture to be reproduced, the second print records the tones of the first print and in addition the next brightest tones, etc., until the last print records substantially all of the tones of the picture to be transmitted. As stated in the said patent and as well known to the art, these prints are formed upon a metal plate by means of a film of hardened gelatin, which acts as an efficient insulator. Hence, when the said plate is connected to one terminal of a source of electric current, and a metal point, which is called a "reader," is connected to the other terminal of the said source of current, and the reader is moved with respect to the print in a helical path, the circuit is made and broken as the reader passes over bare portions of the plate and over portions of the said film of insulating material.

In order to secure perfect recording or transmission of the tone values of a print, it would be necessary for the pitch of the said helical path to be equal to the width or diameter of the reader point. This, however, is impossible for a number of practical reasons, and in actual practice it has been found necessary to impart a definite pitch to the said helical path so that the reader points do not pass over each and every consecutive small area of each print. This results in a

noticeable loss of detail when the reader points simultaneously contact with corresponding small areas of the respective prints, which has been the practice up to the present time.

According to this invention, the reader points are placed so as to simultaneously contact with different small areas of the respective prints, these different small areas comprising a consecutive series.

For example, in Figs. 1-5, the five prints 1, 2, 3, 4 and 5 represent metal plates (preferably zinc plates) having the images of a picture in different tone values reproduced thereon in films of insulating material. These prints 1-5 are depicted as planar, but of course they could be bent around a revoluble cylinder in the well known manner. The reader points 6, 7, 8, 9 and 10, instead of contacting with corresponding small areas of the said prints, contact with small areas which are arranged in what may be termed a diagonal series, the relative location of the said reader points being diagrammatically shown in Fig. 11. That is, the area of print 4 which at any given time is in contact with the reader point 9, is spaced from the corresponding area then in contact with the reader point 10, along a line which is inclined to both edges of the said print 4, although it need not be necessarily a true diagonal.

On each of the prints, five imaginary parallel lines L are depicted and the pitch of the relative movement between each reader point and its print is equal to five times the distance between adjacent lines L . That is, if we assume that the reader point 6 moves over the line L' in one of its transverse movements, it moves over a line in the next transverse movement, which is spaced from line L' by a distance equal to the distance between adjacent lines L .

Assuming that the reader point 10 contacts with the print 5 along the line L^5 , then the reader point 9 contacts with the print 4 along the line adjacent to L^5 , the reader point 8 is spaced for a distance equivalent to two lines, the reader point 7 is spaced for a distance equivalent to three lines, and the reader point 5 is in contact with the line L' . The diameter or width of a reader point is preferably very small, and much less than the distance between consecutive lines L . The respective lines are identified as L' , L^2 , L^3 , L^4 and L^5 .

If the line 11 shown in Fig. 1, for example, has a width substantially equal to the pitch of the path of the reader points, then if all the reader points had the position of point 6 shown in Fig. 1, the said points would first pass along the lines L' and then along a line spaced from the line L' without making contact with the narrow bar of insulating material 11, so that this detail would be wholly lost. However, by having the five points in the position shown in Figs. 1-5, at least three

of such points pass over the portions 11 of the prints so that at least some of this detail is secured in the picture.

Of course, if the portion 11 would correspond to the darkest tone which is being recorded, so that it would appear on only one of the prints, it might be lost from the record or reproduction of the picture, but all areas corresponding to the lighter tones are passed over by two or more reader points so that some of the detail which was formerly wholly lost is reproduced according to this improved method. The portions 12 and 14 of the respective prints illustrate the advantage of having the areas which are simultaneously in contact with the reader points, laterally spaced from each other, this lateral spacing being equal to the pitch of the path of the reader point divided by the number of reader points less one.

Similarly, and as shown in Figs. 6-10, the small areas of the prints which are simultaneously in contact with the reader points are longitudinally spaced. Any suitable ratio may be provided between the longitudinal spacing and the lateral spacing of the small areas of the prints which are simultaneously in contact with the reader points, but I prefer to make the longitudinal spacing greater than the lateral spacing.

I have not depicted in detail the record tape formed to provide a non-pictorial record of the picture, as this is well known in the art.

In order to properly reproduce the picture, the record tape T is caused to move behind a shutter member 15 which is provided with openings 16, 17, 18, 19 and 20, arranged as shown in Fig. 13. Each of the rows of holes T' in the record tape T controls the passage of light through one of said light openings. The light openings 16-20 inclusive may be regulated by means of independently movable shutters, so that the amount of light passed through each of the apertures 16-20, when it is adjacent a perforation of the tape T , can be suitably controlled.

Parallel beams of light are caused to pass through the holes in the record tape T , the light being furnished by a suitable lamp 16' which is associated with a lens system 17. This part of the representation is wholly diagrammatic, as numerous lens systems for producing a beam of parallel rays of light are well known.

The light openings 16-20 are focused upon a sensitive film 21 which is mounted upon a suitable roller, by means of a lens device 18. That is, the lens device 18 does not focus the image of the source of light upon the sensitive film 21, but on the contrary it focuses thereon the five images of the light openings 16-20 which may be arranged as shown in Fig. 14. As shown in Fig. 14 the images of the light openings preferably do not overlap but form separate images which are so closely

adjacent to each other that the effect upon the eye of the observer is the same as though a single spot of light had been focused upon the image. That is, the tone effects upon the 5 reproduced picture are formed by groups of points or dots of varying tone value. These points or dots of the original picture may be referred to as "elemental areas."

The British Patent No. 195,577 before mentioned as well as other patents upon the "Bartlane" process illustrate mechanism whereby the circuits controlled by the five readers control five selector magnets, by means of which one or more of a group of 15 five punches can be selected to punch one or more (up to 5) holes 'T' in the tape T. In the former patents illustrating the "Bartlane" process the number of holes in each row or group on the tape corresponded to the tone value 20 of a single small area of the picture. Under the old method if it was desired to secure fine detail, it was necessary to make the helical path of the reader means of small pitch. This would have required punching a very 25 long tape with a resultant increase in the cost of transmission or reproduction of the tape. According to the improved method set forth herein, each row or group of perforations 'T' corresponds to the tone value of a 30 series or group of different small areas of the picture which is being reproduced so that much finer detail is secured without increasing the length of the tape. In reproduced pictures or the like which have been previously 35 made by means of the "Bartlane" process as well as by other processes, each small area of the reproduced picture corresponded to a small area of the plate used for transmitting purposes. On the contrary, and according to 40 the present invention, each small area of the reproduced picture is a composite representation of a plurality or series of closely adjacent areas of the transmitting plate or plates. Likewise, the perforated tape of the 45 type shown in Fig. 15 and prepared according to previously known methods had a lateral group of perforations which corresponded to the tone value of a single small area of the picture or plate which was being transmitted.

50 According to the present invention, a single lateral group of perforations corresponds to a plurality of closely adjacent consecutive small areas of the picture or plate thereof which is being transmitted.

55 It is not always necessary to have the prints 1-5 of varying tone value, because if it is desired to transmit or record a signature or other black and white matter, said prints could have the same tone value. The improved method enables the recording and transmitting of signatures and the like with much greater detail and accuracy.

Neither is the new method set forth herein limited to the use of a plurality of prints of a picture, signature or the like. For example,

if a single print were employed, the single reader point could be given a longitudinal movement along the line L', and it could then be given four lateral movements so as to consecutively touch the single print along the 70 lines L²-L⁵. The reader could then be given a single longitudinal movement along the line L⁵ and it could then be given four reverse lateral movements until it again contacted with the print along the line L'. That 75 is, the single reader point could be moved along a path generally corresponding to the helical path before mentioned, each intermittent series of movements along this helical path being accompanied with intermittent 80 lateral movements which are successively in opposite directions.

The single reader point could be used to control one of the punches at each of its positions so as to secure the result before mentioned, namely, to have each row or group of perforations on the tape correspond to the tone value of a series or group of areas on the picture, each area corresponding in size to that portion of the picture or print 90 thereof whose tone value can be determined by a single reader point.

Neither is my invention limited to the use of mechanical reader points or mechanical means in general for transforming the tone 95 value of the picture into electrical pulses, as my invention would cover the use of photo-electric reading means embodying the use of photo-electric cells, selenium cells or the like. It has hitherto been known to read the picture either using a single print or a plurality of prints) by causing the reader means to move relatively to the print or prints along a continuous helical line or lines, while producing groups of perforations, each group 100 of perforations corresponding to a group of small areas which were continuously arranged along a continuous line. According to this old method, the small areas of successive groups were arranged along the same continuous line. Assuming for convenience, that the picture to be read has an axis which for example, may be the long edge thereof, the present method is distinguished from the old method in that the areas of successive groups are disposed in zig-zag relationship. Hence a much larger portion of the picture 110 is read because the respective groups of perforations in the tape correspond to successive groups of small areas which are arranged in successive zig-zag relation.

I have shown a preferred embodiment of my invention, but it is clear that numerous changes and omissions could be made without departing from its spirit.

Wherever I have used the term "perforated tape", I wish to include all surfaces upon which markings or operations have been performed which cause portions of the said sur-

face to differ in light value or electrical value from the remainder thereof.

I claim:—

1. In the art of reproducing a picture, those steps which consist in simultaneously causing a series of reader means to co-operate with a plurality of prints of the said picture, the said reader means being caused to simultaneously co-operate with different relative small areas of the respective prints, and combining the readings secured by said reader means to produce composite small areas on the reproduced picture.
2. In the art of reproducing a picture, those steps which consist in simultaneously causing a series of reader means to co-operate with a plurality of prints of the said picture, the said reader means being caused to simultaneously co-operate with different relative small areas of the respective prints, and combining the readings secured by said reader means to produce composite small areas on the reproduced picture, the said small areas of the prints forming a continuous series whose members are laterally spaced from each other.

3. In the art of reproducing a picture, those steps which consist in simultaneously causing a series of reader means to co-operate with a plurality of prints of the said picture, the said reader means being caused to simultaneously co-operate with different relative small areas of the respective prints, and combining the readings secured by said reader means to produce composite small areas on the reproduced picture, the said small areas of the prints forming a continuous series whose members are longitudinally spaced from each other.

4. In the art of reproducing a picture, those steps which consist in simultaneously causing a series of reader means to co-operate with a plurality of prints of the said picture, the said reader means being caused to simultaneously co-operate with different relative small areas of the respective prints, and combining the readings secured by said reader means to produce composite small areas on the reproduced picture, the said small areas of the prints forming a continuous series whose members are laterally spaced from each other, the pitch of the path of the said reader means being substantially equal to the lateral distance between end members of the said series.

5. In the art of reproducing a picture, that step in the art which consists in controlling the passage of light through a series of light openings by passing in front of said light openings a tape having rows of perforations each of which corresponds to the tone value of a diagonal series of successive small areas of a series of prints of the picture to be reproduced, said series of small areas being consecutively arranged in zig-zag relationship, the said light openings also forming a

diagonal series, and focusing the said light openings upon a sensitive film so that the images of said light openings are caused to form a unitary visual record.

6. In the art of reproducing a picture, that step in the art which consists in recording the tone values of groups of small areas of the said picture by means of groups of perforations on a tape, each group of said perforations corresponding to a group of different small areas of the said picture, the successive groups of small areas being arranged in zig-zag relationship.

7. A perforated non-pictorial record of a picture, said record having a plurality of groups of perforations, the perforations in each group corresponding respectively to the tone values of a group of small areas of the said picture, the successive groups of small areas being arranged in zig-zag relationship.

In testimony whereof I affix my signature.

HARRY GUY BARTHOLOMEW.
